SPINDLE RECIPROCATING MECHANISM

Ralph E. Price, Highfield, Md., and Harold E. Balsiger, Waynesboro, Pa., assignors to Landis Tool Company, Waynesboro, Pa.

Application June 23, 1941, Serial No. 399,358

7 Claims. (Cl. 51—34)

This invention relates to metal working machines, particularly grinding machines, and it is an object thereof to provide a spindle mounting whereby a grinding wheel on the spindle may be reciprocated thru a stroke of adjustable length within a predetermined range.

A further object is to provide a novel reciprocating mechanism to effect endwise movement of said spindle.

A further object is to provide resilient means for taking up wear on the thrust member.

A further object is to provide means whereby the same resilient member is used for effecting a part of the reciprocating movement of the grinding wheel.

A further object is to provide manually operated means for shifting said spindle and grinding wheel to grind against a shoulder.

In order to prevent endwise movement of a grinding wheel spindle, a shoulder thereon is usually held against one end of a bearing member by means of a thrust nut on said spindle at the opposite end of said bearing. As the shoulder or nut wears away due to the rotation of the spindle, the wear may be taken up by adjusting said nut. By substituting a spring for the nut and inserting same between the spindle pulley and the bearing, wear will be taken up automatically. If it is desired to grind against a shoulder or to reciprocate the spindle, this spring can be used to provide movement in one direction.

A reciprocating mechanism has also been provided which consists of an annular faced cam rotating inside the spindle in the same direction as the spindle but at a slightly different speed. Said cam urges said spindle to the left thru a single ball in an annular race in said spindle. The thrust take-up spring urges said spindle in the opposite direction.

Figure 1 is a sectional front view of a grinding wheel support showing a fixed stroke reciprocating mechanism.

Figure 2 is an end elevation of the starting knob.

Figure 3 is a sectional view of an adjustable reciprocating mechanism.

Figure 4 is a sectional view of the device of Figure 3 in a non-reciprocating position.

Figure 5 is an end view of the adjusting means in Figure 3.

Figure 6 is an alternate form of our invention.

In the drawings, numeral 10 is a grinding wheel base of the type disclosed in copending application Serial No. 321,310 filed February 28, 55

1940; 11 and 12 spindle bearings mounted therein, 13 a spindle rotatably supported in said bearings, and 14 a thrust shoulder on said spindle. Said shoulder is held against one end of bearing 12 by a spring 15 at the opposite end thereof. One end of said spring bears against a thrust collar 16 which in turn bears against the end of said bearing. Said collar is held against rotation relative to the spindle by a pin 17 therein which projects into groove 18 in spindle 13. The other end of spring 15 bears against a pulley 19 keyed to said spindle and secured thereon by a nut 20. A driving pulley 21 may be mounted in any suitable manner on a motor or line shaft (not shown) and connected to pulley 19 by V belts. A grinding wheel 25 is mounted on the other end of said spindle by means of a collar 26. Said collar fits in a recess in wheel center 27 and holds said wheel and center on said spindle by means of a screw 28 passing therethru and threaded in said spindle.

The means for effecting a reciprocating movement of the spindle 13 consists of an actuating spindle 35 having a flange on one end and supported on spaced needle bearings 36 in a bore 37 in spindle 13. A cam 40 having an annular face is inserted in the inner end of said actuating spindle 35 and held in position by a pin 38. Between said cam and the bottom of said bore is a ball race 39 having an annular groove 41. A ball 42 is held in said groove by the action of spring 15 urging pulley 19 and spindle 13 to the right. Axial movement of said cam and actuating spindle to the right is limited by engagement between a bearing member 45 in actuating spindle 35 and abutment 46. Said abutment is mounted for self alignment on the spherical end 47 of an adjusting screw 48 and secured thereon by a pin 49. Said screw is adjustably mounted in a bracket 50 on wheel base 10. A split nut 51 may be locked to said screw 48 by means of clamping screw 52. Actuating spindle 35 is rotated by means of a grooved pulley 55 secured by any suitable means to the flanged portion of said actuating spindle 35. Stepped pulley 19 and pulley 55 are both driven from driving pulley 21. Pulley 55 has a different diameter from either of the stepped portions of pulley 19 so that there is a slight difference in speed between spindle 13 and actuating spindle 35. This difference in speed determines the rate of reciprocation of spindle 13.

For grinding against a shoulder, a roller 66 is provided engaging a shoulder 68 on spindle 13. Said roller is eccentrically supported on a ver-

tical axis in shaft 67. Said shaft is rotatably supported in a portion 68 of wheel base 10. A handle 69 is secured to a protruding end of shaft 67.

In Figures 3 and 4 is shown a form of our invention in which the reciprocating stroke may be adjusted. Instead of an actuating spindle mounted on needle bearings, a cylindrical member 75 rotatably supported in the bore 76 in spindle 70 is used. Said bore provides the bearing surface for said cylindrical member. The inner end of said cylindrical member has a slot 77 to which a member 78 is pivotally attached by means of a pin 79. At the end of said bore is the ball race 39 with the annular groove 41 for ball 42.

When the face of member 78 is parallel to race 39 as shown in Figure 4, there is no reciprocating movement. Any variation from this position about pin 79 would result in a reciprocating movement of a length depending upon the adjustment of said member. Such adjustment may be effected by means of a pair of rods 80 and 81 passing axially thru member 75 and engaging opposite portions of pivoted member 78. The position of said member 78 may be adjusted by manipulating set screws 82 and 83 which effects adjustment of rods 80 and 81. The amount of adjustment may be indicated by graduations 84 on member 75 surrounding screw 82. If necessary, said rods and screws may be locked in any adjusted position by the use of lock screws in conjunction with said adjusting screws. Means for starting and stopping spindle reciprocation with this form of our invention consists in a ring shaped member 85 having an annular cam surface 86. Said member is rotatably supported on a double row ball bearing 87 on member 75. A handle 88 having a hub portion 89 which serves as a cover for the end of member 75 is secured to said cam 86 by screws 90. In the center of said hub portion is an opening 91 thru which screws 82 and 83 may be reached for adjustment. A bracket 92 secured to wheel base 10 supports a roller 93 in contact with said cam surface 86.

Ball 42 and spindle 70 are urged to the right by a spring 95 on said spindle. One end of said spring engages the left hand bearing 11, the other end engages a shoulder 96 on said spindle. Like spring 15 in Figure 1, spring 95 serves to take up wear on the thrust surfaces as well as to provide a part of the reciprocating movement of said spindle.

Another form of adjustable reciprocating mechanism is shown in Figure 6. In this form adjustable member 100 has a portion 101 forming the inner race of a ball bearing. The outer race 102 has a portion 103 which extends radially inward to provide a face portion. On the spindle 70, a member 104 has a protruding portion 105 which engages the face 103 of outer race 102.

Operation

In order to start the reciprocating movement of spindle 13, abutment 46 is adjusted by means of screw 48 into contact with bearing 45 in actuating spindle 35 until the spindle is moved axially away from positive thrust bearing by movement of cam 40 against ball 42. The difference in rate of rotation causes said ball to move along groove 41. As said ball moves across the high point of cam 40, spindle 13 is moved to the left against the

action of spring 15 since actuating spindle 35 and cam 40 are held against axial movement by abutment 46. As said ball moves toward the low point of cam 40, spring 15 urges pulley 19 and spindle to the right. The rate of reciprocation is determined by the difference in angular speed of the spindle 13 and race 39, and the cam 40. The action of ball 42 rotating between cam 40 and race 39 provides a further reduction of one-half in reciprocating speed.

To stop the reciprocating movement, abutment 46 is withdrawn. Spindle 13 is thus free to move to its extreme right hand position under the influence of spring 15.

The form of the invention shown in Figures 3 and 4 operates on the same principle as that shown in Figure 1. To start reciprocation, lever 88 is shifted so that the cam surface 86 rotating against the fixed roller 93 causes members 75 and 78 to move to the left and in the position shown, to move spindle 70 in the same direction against the action of spring 95. As ball 42 moves toward the low portion of member 78, spring 95 will shift spindle 70 to the right. To stop reciprocation, lever 88 and cam 86 are returned to their original position and the action of member 78 on ball 42 is such that said member along with member 75 is moved to the right to a point where it is no longer effective to impart a reciprocating movement to spindle 70.

The extent of reciprocation is determined by the angle between the face of member 78 and its axis of rotation. This may be adjusted from zero to a predetermined maximum. Adjustment may be effected by removing lock screws, and adjusting screws 82 and 83 in opposite directions to effect a corresponding adjustment of rods 80 and 81. Member 78 is thus tilted to the desired position as indicated by graduations 84 around screw 82.

With the type of reciprocating device disclosed above, it is desirable that the rate of reciprocation shall vary directly with change in load. As the load increases the wheel slows down, the motor also slows down but by a smaller amount. The reciprocating mechanism will slow down only in proportion to the reduction in motor speed. The difference in angular speed will be decreased and likewise the rate of reciprocation.

If it is desired to increase the rate of reciprocation with the increase in load, then a smaller pulley should be used on the reciprocating mechanism than on the spindle. As the spindle slows down the reciprocating mechanism will also slow down but at a different rate. However, the difference in speed between the spindle and reciprocating mechanism will be increased and likewise the rate of reciprocation.

If it is desired to start the reciprocating movement when the load reaches a certain point, the spindle pulley and the reciprocating mechanism pulley should be the same diameter. As soon as the spindle pulley slows down, the reciprocating mechanism pulley will slow down also but to a less extent. The difference in speed of the two parts will result in a reciprocating movement of the spindle.

We claim:

1. A grinding wheel mounting including a wheel support, a spindle rotatably mounted therein and means for driving same, a grinding wheel on said spindle, mechanism for effecting a reciprocating movement of said spindle including a member rotatable with said spindle, a sec-

ond member rotatable at an angular speed differing slightly from that of said spindle, one of said members having an operative surface perpendicular to its axis of rotation, the other of said members having an operative surface tilted at an angle to its axis of rotation, a rolling member adapted to move on said perpendicular surface in contact with said tilted surface, and means for adjusting the angle at which said surface is tilted.

2. A grinding wheel mounting including a wheel support, a spindle rotatably mounted therein and means for driving same, a grinding wheel on said spindle, mechanism for effecting a reciprocating movement of said spindle including a member rotatable with said spindle, a second member rotatable at an angular speed differing slightly from that of said spindle, one of said members having an operative surface perpendicular to its axis of rotation, the other of said members having an operative surface adjustably attached thereto, means for changing the angle between said surface and its axis of rotation including a pair of rods slidably mounted in said second member and engaging said adjustable surface, and means for adjusting said rods.

3. A grinding wheel mounting including a wheel support, a spindle rotatably mounted therein, and means for driving same, a grinding wheel on said spindle, mechanism for effecting a reciprocating movement of said spindle including a member rotatable with said spindle, a second member rotatable at an angular speed differing slightly from that of said spindle, one of said members having an operative surface perpendicular to its axis of rotation, the other of said members having an operative surface adjustably attached thereto, means for changing the angle between said surface and its axis of rotation, including a pair of rods slidably mounted in said second member and engaging said adjustable surface, means for adjusting said rods, and means for determining the length of the reciprocating movement by indicating the extent of said adjustment.

4. A reciprocating mechanism for a grinding wheel comprising a support, a grinding wheel spindle rotatably mounted therein, means for rotating said spindle, a member mounted for rotation independently of said spindle, means for

rotating said member at a different angular rate than said spindle, a second member rotatable with said spindle, one of said members having a face perpendicular to its axis of rotation, the other member having a face at an angle less than 90° to its axis of rotation, a rolling member adapted to be rolled between said faces for effecting a relative reciprocating movement therebetween at a rate determined by the difference in angular speeds between the spindle and said first mentioned member, and means for starting and stopping said reciprocating movement during rotation of said spindle.

5. A device of the type set forth in claim 4 including means for effecting endwise movement of one of said members toward the other whereby to initiate said reciprocating movement.

6. A grinding wheel mounting including a wheel base, a spindle rotatably mounted in bearings in said base, means for rotating said spindle, a member mounted for rotation independently of said spindle, means for rotating said member at a different angular rate than said spindle, an annular cam surface on one of said parts, connections between said cam surface and said other part such that a relative reciprocating movement is effected between said parts, and means for shifting one of said members axially for rendering said connections operative or inoperative.

7. A machine tool including, in combination, a rotatable element mounted for axial movement, a pulley in driving relation to said element, an additional pulley mounted adjacent to said first pulley and rotatable independently thereof, a cam, a connection between said cam and one of said pulleys, means providing connection between said cam and said rotatable element such that the element is moved in reciprocation following the shape of the cam, means for driving said pulleys at relative speeds for effecting rotation and reciprocation of said rotatable element, an abrading element actuated by said rotatable element in rotation and reciprocation, and means for rendering said second connection operative or inoperative for starting and stopping said reciprocating movement.
